UNITED STATES PATENT OFFICE.

FRITZ ALDENDORFF, OF MORTSEL, NEAR ANTWERP, BELGIUM, ASSIGNOR TO WESTERN ELECTRIC COMPANY, OF NEW YORK, N. Y., A CORPORATION OF ILLINOIS.

CONVERSATION-REGISTERING CIRCUITS FOR MACHINE-SWITCHING TELEPHONE SYSTEMS.

1,147,997.

Specification of Letters Patent. Patented July 27, 1915.

Application filed June 30, 1913. Serial No. 776,614.

To all whom it may concern:

Be it known that I, FRITZ ALDENDORFF, a subject of the King of Great Britain, residing at Mortsel, near Antwerp, in the 5 Province of Antwerp and Kingdom of Belgium, have invented a certain new and useful Improvement in Conversation-Registering Circuits for Machine-Switching Telephone Systems, of which the following is a 10 full, clear, concise, and exact description.

My invention relates to machine-switching telephone systems in which the connections made between different stations are registered and charged to the stations that initiate the calls.

A feature of the invention consists in the manner in which the recording circuit is closed through a wire that serves as part of a circuit for other purposes such as restoring the switches used for a connection to their normal positions, preparing a circuit that momentarily removes the busy condition from a calling line in the case of a reverting call in a party line system and for 20 disconnecting devices from a calling line after they have performed their functions so as to prevent them from absorbing any of the talking current. According to the invention all these functions are accomplished 25 over a single wire by straight battery currents, that is without employing graded or differential currents. Synchronous circuit changers are used which apply portions of the 30 various circuits to different points of the 35 wire at identical moments.

Another feature of the invention is the provision of a special conversation meter for each station of a party line and of means for connecting the meter corresponding to 40 the calling station to the meter circuit. The meter selecting devices are also made to act as a means for starting a switch or switches that connect a calling line to an idle link circuit through which the circuit of the calling line is extended to the wanted line.

A further feature of the invention resides in means for controlling the closure of a meter circuit that act only in response to the answering act of the called station of a 50 party. This is important in cases of reverting calls. If in such cases the meter circuits at the exchange were to be closed in the well-known manner, by the mere clo-

sure of the circuit of the called line on the response of the called subscriber it is evident that the meter circuits would be caused to act in the case of reverting calls, even if the called station did not answer because at the moment the reverting connection is made the circuit of the party line is already closed 55 at the calling station. Hence means must be provided for closing the meter circuit that do not respond to the ordinary closure of the loop of the wanted line. The means provided by this invention consist of contacts attached to the switchhooks of the subscriber's station that momentarily establish a special condition of the line that differs from the normal and from the closed speaking condition, and these means consist 60 further of devices that respond only to the aforementioned special condition.

Another feature of the invention consists in providing improved devices for removing the busy condition from a calling party line 65 at the moment a reverting connection is made.

The improvement consists in so arranging these devices that this busy potential is removed only at the instant the reverting 70 connection is made, and not as in systems heretofore proposed, also incidentally at other instants.

Further features of the invention will appear in the following specification.

The invention is shown in the accompanying drawings.

Figure 1 illustrates the circuits of a distributing switch, which connect a calling line to a free trunk leading to a selector. 90 In this figure the circuits of the conversation meters belonging to a party line are also illustrated. Fig. 2 represents the circuit of a first selector. Fig. 3 shows the circuits of a final selector. Figs. 4, 5, 6 and 7 95 show the party line subscriber equipments. Fig. 8 illustrates the impulse transmitter partly in perspective and partly diagrammatically. Fig. 9 is a diagrammatic representation of the impulse transmitter, and Fig. 10 shows a special relay designed for a positive release.

201 and 202 represent the two limbs of a line connected to the exchange. It will be assumed that four subscribers' equipments 105 as illustrated in Figs. 4, 5, 6 and 7 are con-

nected to this line. As illustrated in Figs. 4, 5, 6 and 7, respectively, the subscribers' equipments are provided with contact springs 600, 601, 600', 601', 600'', 601'', 600''', 601''' and 602 respectively. The switch hook lever 603 is provided with an oblique cam 604 which is insulated from the hook. Upon the removal of the receiver, the upward movement of the switch hook 10 pushes the spring 600 into contact with spring 601. In the case of the station shown in Fig. 4, this upward movement of the switch hook momentarily grounds the line 201 through a resistance 605. In the station 15 illustrated in Fig. 5, the line limb 202 is momentarily grounded, and in the station shown in Fig. 7 line limb 201 is momentarily grounded through a resistance 606 and the limb 202 is simultaneously 20 momentarily directly grounded. The upward movement of the switch hook 603'' in the subscriber's equipment shown in Fig. 6 causes a momentary contact between springs 600'' and 601'', which momentarily short 25 circuits the line without any intervening resistance, or, in other words, the loop consisting of the line leads 201 and 202 is short circuited before the switch hook closes the loop through contact 607 and hence through 30 the transmitter 608 and the winding 609 of the induction coil. This momentary grounding of the one or the other or both of the line limbs 201 and 202 in the manner illustrated is the means by which the proper 35 meter is connected to the meter circuit of the exchange. The momentary short circuiting of the line loop in the manner shown in Fig. 6 does not perform any useful function when this subscriber is calling. This 40 momentary short circuiting is useful only when this subscriber is the called party. In this case the momentary short circuiting of the line loop causes the relay 610 at the final selector to attract its armature momentarily 45 and thus to energize relay 619 which in turn moves the side switch at the final selector from the ringing to the talking position as will be more fully explained hereinafter.

By the four different switching measures 50 described, the relays 203, 204, 205 at the exchange are influenced in different ways, so that these relays connect either the meter 206, 207, 208 or 209 to the meter circuit 210.

If station I of the line 201, 202 calls, wire 55 201 will be momentarily earthed, and the consequence of this is the excitation of relays 203 and 205 in a circuit which may be traced from earth through battery 211, winding of relay 205, winding of relay 203, wire 3, armature 4 of line extending relay 212, wire 201, switchhook of station I to earth. By the actuation of relays 203, 205, a current is caused to flow through the meter 60 connecting relay 213. This current may be traced from the positive pole of the ex-

change battery through armature 6 of relay 205, thence through 7, 8, 9, 10, 11, meter connecting relay 213 to the negative pole of the battery. The relay 213 closes a locking circuit for itself through armature 14, wire 70 13, armature contact 12 of restoring relay 217, to the positive pole of the battery. The meter 206 which corresponds to the calling station No. I of line 201, 202 is now connected through the armature contact 15 of a 75 meter connecting relay 213 to the meter circuit 210.

If a station II of line 201, 202 had called, this would have caused the energization of relays 204, 205 instead of relays 203 and 205, 80 and this would have resulted in the energization of the meter connecting relay 214 by a current flowing over the following path:—Positive pole of the battery, contact 6, wires 7, 16, contact 17 of relay 204, wire 85 18, contact 19 of relay 203, wire 20, meter connecting relay 214 to the negative pole of the battery. The meter connecting relay 214 would have closed a locking circuit for itself through 22, 21, 13, 12, to the positive 90 pole of the battery, and the meter 207 corresponding to the calling station II would be connected to the meter circuit 210 through the armature 23 of a meter connecting relay 214. 95

If it had been a station III that called, the switchhook of this station would have earthed wires 201, 202, the one wire being earthed direct, the other through a resistance so that the windings 1 and 2 of the differential relay 205 would have been energized by currents of different strengths, causing this relay to attract its armatures, this relay being so wound as to be unaffected when currents of equal strengths flow through windings 1 and 2. Thus the three relays 203, 204 and 205 all pull up together 100 only when station III calls. This results in the energization of the meter connecting relay 215 by a current flowing from the positive pole of the battery through 6, 7, 8, 9, 24, 23, 26, meter connecting relay 215 to the negative pole of the battery. The meter connecting relays 213, 214 are prevented 110 from being energized by the opening of armature contacts 10 and 19. The meter connecting relay 215 closes a locking circuit for itself through its armature 27, wires 28, 13, and armature contact 12. The meter connecting relay 215 connects meter 208 that 120 corresponds to station III through its armature contact 29 to the meter circuit 210.

In case station IV calls, the switchhook 125 earths neither of the wires 201 and 202, but simply closes the line loop in the ordinary manner. This results in only the relays 203, 204 being energized, the differential relay 205 remaining inert. By the relays 203, 204 being energized alone, the meter connecting relay 216 is actuated by current 130

flowing from the positive pole of the battery through armature 30, wire 31, armature 32, armature 33, wire 34', armature 35 of relay 218, meter connecting relay 216 to the negative pole of the battery. The meter connecting relay 216 closes a locking circuit for itself through 36, 37, 13 and 12, and by means of its armature contact 38 it connects the meter 209 corresponding to the calling station IV to the meter circuit 210.

The purpose of relay 218 will now be explained. From the above description it is seen that the meter 209 is connected to the meter circuit 210 by means of the meter connecting relay 216 through the energization of the relays 203 and 204. The relays 203, 204 are, however, energized by the calling of any of the stations I, II, III, IV as soon as the switchhook of any of these stations closes the line loop. For this reason the circuit of the meter connecting relay 216 must be open in all cases in which the relays 203 and 204 shall not effect the connection of the meter 209 to the meter circuit 210, so this opening of the circuit of the meter connecting relay must take place before the closure of the line loop 201, 202. This opening of the meter connecting relay circuit is caused by the relay 218. This relay is energized the moment any one of the meter connecting relays 213, 214, 215 is actuated and the circuit through the relay 218 is closed either by armature 39, 39' or 39'' according as the meter connecting relay 213, 214 or 215 is energized. The closure of either of the contacts 39, 39', 39'' takes place a moment before the subscriber's loop 201, 202 is closed, so that by the time the relays 203, 204 are energized by the closure of the loop, the armature 35 of relay 218 will already have opened the circuit of the meter connecting relay 216 at the armature 35.

The relays 203 and 204, besides serving to close the circuit of the meter connecting relay 216, are also used for closing the circuit of a relay 219, which relay controls the circuit of the stepping or power magnet 220 of the distributing switch. This distributing switch, having movable contact arms 250, 251 and 252 that are driven step by step in a known manner by the magnet 220, so as to wipe over sets of fixed contacts connected to trunks 253, 254, 255 leading to first selectors, Fig. 2. The moment the line loop 201, 202 is closed, and the relays 203, 204 energized, a circuit is closed from the positive pole of the battery through the armature 40, wire 41, armature 42, wire 43, contact 45 of off-normal switch, motor control relay 219, contact 46 of off-normal switch, to earth. The relay 219 now attracts its armatures, and by means of contact 47 closes a circuit, which may be traced from the negative pole of the battery through an interrupter 238, wire 48, arma-

ture contact 47, stepping magnet 220, positive pole of the battery. The stepping magnet 220 now causes the arms 250, 251 and 252 to travel step by step over sets of fixed contacts connected to the trunks leading to the first selector, Fig. 2. The moment the contact arms 250, 251, 252 leave their normal position the contacts 45, 46 and 51 of an off-normal switch belonging to the distributing switch are opened, and the contacts 49, 50, 52, 53, 55 and 56 of this off-normal switch are closed. For convenience of illustration, the contacts of this off-normal switch are shown in different parts of the drawing, although in practice they will all form part of one and the same switch.

By the closure of contact 52, the test wire 256 extending from the calling line to the contact banks of the final selectors of the exchange is earthed, and the busy condition of the calling line is thus indicated.

The test circuits of the distributing switch, Fig. 1, are so arranged that the test relay 219 remains energized as long as the test brush 252 keeps striking earthed test contacts 257, Fig. 2. As long as this continues the circuit of the test relay 219 will remain closed, current flowing through the test relay over a circuit leading from the negative pole of the battery to armature contact 34, contact 55 of off-normal switch, which is now closed, test relay 219, test wire 57, test brush 252, fixed contacts 257 of the busy trunks, thence through the test wires 58 to the test brushes 252 of other distributing switches that are keeping the trunks busy that are being traversed by the hunting switch, wires 57 of the other distributing switches, contacts 56 of the switches, armature contacts 59, and wires 60 of same, movable contact arms 61 of synchronous circuit changers belonging to the other distributing switches, coils 62 and thence to earth. The moment the test brush 252 of the distributing switch that is hunting for an idle trunk reaches the fixed contact 257 belonging to an idle trunk, the circuit traced above for the test relay 219 will no longer be closed, and the test relay 219 will allow its armatures to drop back. The armature contact 34 of the test relay will open before contact 59 is closed, so that the circuit of the test relay cannot be reclosed immediately after through the circuit leading from the negative pole of the battery through 34, 63, 55, 219, 56, 59, 60, 61, 62 to earth. The moment the contact 59 is closed, the test wire of the trunk that was found idle is earthed over a path leading from the fixed contact 257 through 252, 57, 56, 59, 60, 61, 62 to earth. The deenergization of the test relay 219 causes the closure of the line-extending or cut-off relay 212, through a circuit from earth through 64 and through a 130

contact 49 of the off-normal switch 65, 212 to the negative pole of the battery. By the energization of the relay 212 the wires 201, 202 are separated from the relays 203 and 204, and are extended to the movable contact arms 250 and 251 of the distributing switch, and through these movable arms to the first selector, Fig. 2. When the line is thus extended to the first selector the relays 224 and 225 are energized. In order to establish the desired connection through the automatic switches at the central office, the calling subscriber now sends impulses to the exchange by working his impulse transmitter.

The impulse transmitter is shown in Figs. 8 and 9. 700 represents a disk that may be turned about a shaft 701 by the well known type of finger wheel. The finger wheel for turning the disk 700 forward and the spring for returning the same to its normal position when the finger wheel is released, are omitted as are also all other parts in connection with the impulse transmitter which are not essential to make it comprehensive. The disk 700 is divided into two parts, 702 and 703. These parts are insulated from one another. The part 702 of the disk 700 consists of an electric conductor on the surface of which a brush 704 makes contact, which in the normal position of the disk 700 bears upon an insulating portion 705. The purpose of the disk 702 is to ground the brush 704 whenever the disk 700 is moved out of its normal position. The ground connection to the disk 702 is indicated at 706. The part 703 of the disk 700 is insulated and is equipped with a number of pins 707', 707², 707³, 707⁴ and 708 extending outwardly from its surface. The pin 707' engages a spring 709 when the disk is turned out of its normal position. The pin 708 in the same manner engages with the contact spring 710. When the disk 700 is turned forward as indicated by the arrow, the springs 709 and 710, which are normally in contact with spring 711 and 712 respectively, are merely moved farther in the direction of contact. Thus, when a calling subscriber removes his receiver from the hook 603, which in turn closes the line circuit at contact 607 and then turns the disk 700 in the direction indicated by the arrow, the brush 704 will ground to two line limbs 201 and 202 through the grounding disk 702. Immediately after the brush 704 commences riding upon the conducting portion 702, the pin 708 sweeps past the spring 710. Directly after this the pins 707' commence sweeping past the spring 709. After the subscriber turns the finger wheel from the third hole to the stop (not shown) and then releases the finger wheel, the disk 700 will return to its normal position and in this movement it will first open

three times by opening the contact between springs 709 and 711, due to the action of the pins 707', 707² and 707⁴ acting upon the contact spring 709. The instant after the last pin 707' has swept past the spring 709, the pin 708 pushes the spring 710 out of contact with spring 712. The above result is obtained because of the fact that pins 707 and 708 move the springs 709 and 710 in a reverse direction in the return movement of the disk to that in which they are moved when the disk 700 is moved in the forward direction. Thus when the disk 700 is turning back to its normal position, the two line limbs 201 and 202 are kept grounded by the brush 704 and the grounding disk 707², except during the interval when the pins 707', 702, etc., push the spring 709 out of contact with spring 711. Each time this occurs, the earth connection is momentarily removed from line limb 201. The backward movement of the disk 700 likewise causes the pin 708 to move the spring 710 out of contact with spring 712 and, consequently, the ground connection is momentarily removed from the line limb 202. The ground connection will be removed from both line limbs 201 and 202 the moment after the pin 708 leaves the spring 710, due to the fact that the brush 704 will then rest upon the insulated portion 705. Fig. 9 shows the parts shown in Fig. 8 diagrammatically. In this figure the surface of the disk is schematically shown as a plane surface. Corresponding parts of these two figures are marked with like reference characters. Each time the impulse transmitter is operated, the wire 202 is earthed, and then the wire 201 is interrupted a number of times, this number corresponding with the digit of the number of the subscriber wanted. The interruptions of the line wire 201 cause vibrations of the armature 66 of the relay 224 at the first selector. The armature 66 sends impulses through the lifting magnet 237 of the first selector, which then raises the arms 300, 301 and 302 to the desired level of bank contacts. After the contact arms 300, 301, 302 have been raised to the desired level, the wire 201 is earthed at the calling station, while the connection through wire 202 is interrupted. This interruption in the wire 202 results in the deenergization of the line relay 225. The moment the selector shaft carrying the brushes 300, 301, 302 was raised out of its normal position, the contacts 68 and 69' forming a part of an off-normal switch were closed, so that on the momentary deenergization of the relay 225 a current impulse flows from the negative pole of the battery through armature 70, contact 68, contact arm 69 of a synchronous circuit changer associated with the first selector, driving magnet 227 of the circuit changer to the positive pole of the battery.

The impulse through the driving magnet 227 of the synchronous circuit changer causes it to step its arms 69, 70, 71, 73, 74, 75, 76 and 78 into their positions II. A circuit for 5 the test relay 234 of the first selector is then closed immediately the line relay 225 is energized again from the negative pole of the battery through contact 79, 234, switch arm 73, wire 80, resistance 231, rotary off-normal contact 81 to the positive pole of the battery. A current will also flow over wire 95 and through switcharm 69 through the driving magnet 227 of the synchronous circuit changer. Shunt 231 will not allow sufficient 10 current to flow through the driving magnet 227 to energize it. The energization of the relay 234 results in the energization of the rotary magnet 235 of the first selector by impulses flowing from the negative pole of the battery 15 through armature contact 82, rotary magnet 235, wire 83, switcharm 71 of circuit changer, interrupter 236 to the positive pole of the battery. After the rotary magnet 235 has turned the brushes 300, 301, 302 one step, 20 the rotary off-normal switch 81 is opened and the test relay 234 now receives current over the earthed test wires of busy trunks, the test wires of busy trunks being earthed in a manner that will be presently described. 25 30 While the selector is testing for busy trunks, the test relay 234 and the driving magnet 227 will be in series in a circuit from the negative pole of the battery through 79, 234, 73, 80, 305, 69, 227 to the positive pole of the 35 battery. The windings of the relays 234 and 227 are so dimensioned as to prevent either of these magnets being actuated or influenced when connected in series with each other. 40 The test brush 302 is made so broad that it touches another fixed contact 303 before leaving the last. The moment the test brush 302 is set on to the fixed test contact 303 of an idle trunk, the current flowing from the 45 test relay 234 is weakened so much as to cause its armatures to retract, whereupon the armature contact 82 opens the circuit of the rotary magnet 235. Immediately after the driving magnet 227 of the synchronous circuit 50 changer is energized by a current flowing from the negative pole of the battery through 85, 84, 69, 227 to the positive pole. This causes the driving magnet 227 to move the arms of the circuit changer into their third 55 position III. The moment this third position is reached, the test brush 302 is earthed through the following circuit:—302, 232, switcharm 78, test wire 58 that leads to the distributing switch, test brush 252 of distributing switch, 57, 56, 59, 60, 61, 62, earth. The resistance of the driving magnet 62 belonging to the synchronous circuit changer at the distributing switch is so low that the connection of the test wires 58 and 304 65 through it to earth establishes the busy con-

dition of the trunks leading from the distributing switch to the first selector, and from the first selector to the final selector.

In case the calling subscriber replaces his receiver and abandons the call before the first selector has found an idle trunk leading to a final selector, a special release circuit will come into action, this circuit consisting principally of the contacts 86, 87, switcharm 74, relay 306, and the vertical off-normal switch 69'. If the calling subscriber abandons the call before the first selector has reached an idle trunk, the deenergization of the relays 224 and 225 will result in the closure of the contacts 86 and 87, and the 80 current will flow from the negative pole of the battery through 86, 87, 74, 88, 306, 69' to the positive pole.

It is to be noted that the moment a first selector is seized by a distributing switch, 85 its lifting magnet 237 receives an impulse causing the selector shaft to take an idle step, which results in the closure of the vertical off-normal switch 69'.

The current flowing in the circuit described above through the relay 306 causes this relay to be energized, and to close a locking circuit for itself through its contact 89. It also closes a contact 90, and thus connects an interrupter 229 to the test wire 230. 95 The interrupter now intermittently connects the negative pole to the test wire, and energizes the driving magnet 227 and 62 of the synchronous circuit changers at the first selector, and at the distributing switch. The 100 synchronous circuit changers are designed to take one step the moment their driving magnets are energized, and to take a second step the moment the energization of their driving magnets ceases. In the interval between two energizations of their driving magnets, the switcharms of the synchronous circuit changers travel over the short contacts indicated between the long contacts I, II, III and so forth. By providing contacts 105 that are momentarily touched by the switcharms of the synchronous circuit changers in the intervals between the impulses that flow through the driving magnets, circuit controlling functions may be caused to take 110 place during the said intervals. The circuit controlling functions employed in this system will be explained presently.

It has now been explained how a subscriber by prematurely replacing his receiver 120 causes impulses to be sent from the interrupter 229 through the driving magnets 62 and 227 of the synchronous circuit changers belonging to the distributing switch, and to the first selector. If the calling subscriber 125 abandons the call at a moment when the first selector is hunting for a final selector the switch arms of the synchronous circuit changer at the first selector will be in their position II. The abandoning of the call 130

and the consequent closure of the contacts 86 and 87 will, therefore, result in the switcharms of the synchronous circuit changer being moved by an impulse flowing 5 through the interrupter 229 and through the contact 90, half the distance from positions II to the positions III. The moment the impulse through the interrupter 229 and the contact 90 ceases, the switcharm 74 and the 10 other arms of the synchronous circuit changer move to position III, and from this moment the driving magnet 62 of the circuit changer belonging to the distributing switch will also receive impulses through the interrupter 229 and the contact 90. Thus after 15 the switcharms of the synchronous circuit changer at the first selector have reached the position III, each new impulse sent by the interrupter 229 into the test wire 230 will 20 result in a simultaneous energization of the driving magnets 227 and 62 of the synchronous circuit changers at the first selector, and at the distributing switch, and each impulse will cause the switcharms of both 25 circuit changers to progress half the distance between two contacts—for instance III and IV, and after each impulse ceases, the switcharms will execute another half step so as to reach the succeeding long contact. The switcharms of the circuit changer 30 at the first selector will be caused to move forward step by step in the manner described, until they reach the long contacts V, and the switcharm 61 of the circuit changer 35 at the distributing switch will travel around in synchronism with the switcharms of the circuit changer at the first selector until it reaches the long contact III.

The next impulse sent by the interrupter 40 over the wire 230 will result in the switcharm 74 traveling half the distance between the contacts V and VI and in the switcharm 61 traveling half the distance between the contacts III and IV. The moment this last impulse from the interrupter 229 ceases, the switcharms 74 and 73 and all the other arms of the circuit changer at the first selector will execute a further step, and in doing this the arm 74 brushes past a contact 228, and the arm 73 makes a momentary contact with the short contact 91. The arm 61 of the circuit changer at the distributing switch also executes a step from the point half-way between III and IV synchronously 55 with the arms 74 and 73 at the first selector. The arm 61 brushes past the contact 223 at the same moment that the arms 74 and 73 brush past the contacts 228 and 91. At the moment when the arms 73, 74 and 61 touch 60 their respective contacts 91, 228 and 223, the release magnets 233 and 217 of the first selector and the distributing switch are energized. The current that energizes the release magnet of the first selector flows from 65 the negative pole of the battery through 86,

87, 74, 228, 230, 80, 73, 91, 233 to the positive pole of the battery, and the current through the resetting relay 217 of the distributing switch, Fig. 1, flows from the negative pole of the battery through 86, 87, 74, 228, 230, 70 226, 78, 58, 252, 57, 56, 59, 60, 61, 223, 217, 50 to the positive pole. The release relay closes a locking circuit for itself through its armature contact 93. By closing its armature contact 94, the release relay 217 connects the turning magnet 220 of the distributing switch to the interrupter 238, so that impulses will now flow through the turning magnet 220 until the brushes 250, 251, 252 of the distributing switch reach 75 their normal positions, in which the off-normal contact 50 is opened, and in which the other contacts of the off-normal switch are caused to assume their normal positions. The opening of the contact 50 causes the de-energization of the release relay 217, and all 80 parts of the distributing switch will then have regained their normal positions.

It has now been described how the switches at the exchange are restored to 90 their normal positions in case a subscriber abandons the call before the group selector, Fig. 2, establishes a connection with an idle trunk leading to a final selector.

We will now consider the case where the 95 subscriber abandoned the call when the group selector had made connection with a trunk leading to a final selector. In this case, the moment the connection is extended to the final selector, the relays 500 and 501 are energized. Contact 99 is immediately 100 closed and a circuit is formed which may be traced from the negative pole of the battery through 99, arm 526 of side switch, lifting magnet 502 to the positive pole of the battery. The selector shaft is thus raised so as to take an idle step and close a contact 508 of a vertical off-normal switch. The moment the calling subscriber replaces his receiver in abandoning the call, the contacts 600 and 601 of relays 500 and 501, which were opened before the off-normal contact 508 was closed, will now establish a circuit which may be traced from the negative pole 105 of the battery through interrupter 521, contacts 601, 600, wire 124, switcharm 514 of synchronous circuit changer, driving magnet 509, off-normal contact 508 to the positive pole of the battery. The impulses sent by the interrupter 521 through the driving magnet 509 also flow back over wire 304 to the driving magnets of the synchronous circuit changers at the group selector and the distributing switch, and thus the switcharms 110 of all the synchronous circuit changers are 115 stepped forward in synchronism.

In taking their third step, after the impulses through contacts 601 and 600 commenced the release magnet at each selector 120 is energized and the switches restored to 125

- their normal position. It will be remembered that when the connection was extended to the final selector at the group selector, the switch arms of the synchronous circuit changer at the group selector were stepped into their position III. Therefore the third impulse that flows after the contacts 601 and 600 are closed, due to the calling subscriber replacing his receiver, will cause the switcharms of the synchronous circuit changer at the group selector to pass from position V to position VI. The switcharm 61 of the synchronous circuit changer at the distributing switch Fig. 1 is in its position III at the moment the impulses commence flowing through the contacts 601 and 600. Therefore the third impulse that flows through the contacts 600 and 601 will cause the switcharm 513 of the synchronous circuit changer at the final selector to pass from its position III to IV, the switcharm 73 at the group selector to travel from position V to position VI and the switcharm 61 at the distributing switch to move from position III to position IV. In traveling from position III to IV the switcharm 513 of the synchronous circuit changer at the final selector momentarily connects the negative pole of the battery to the wire 304 that extends back to the group selector and distributing switch, therefore at this moment an impulse will flow from the negative pole of the battery through the release magnets at each switch—that is, through the magnet 510 at the final selector, 233 at the group selector and through the release relay 217 at the distributing switch, Fig. 1. The switches will then all be restored to their normal positions.
- It must be pointed out that the synchronous circuit changers are so arranged that when their switcharms have passed from the first position to the last position shown on the drawings, they are ready to recommence a new cycle of circuit changes corresponding in character and sequence to those effected in passing from positions I to VI, Fig. 2, or I to IV, Figs. 1 and 3.
- We will now consider the case where a connection is made with an ordinary line and the line desired is not busy. The calling subscriber works his impulse transmitter, which earths the wire 202 and interrupts the wire 201 in the manner already described, and thus causes the relay 500 to send the desired number of impulses through the lifting magnet 502. By this means, the brushes 504, 505, 506 of the final selector are raised to the desired row of bank contacts. A changeover impulse which causes the relay 501 to allow its armatures to retract then ensues, and a changeover impulse flows from the negative pole of the battery through 96, 97, 98, side switch driving magnet 519, vertical off-normal switch 507, to earth. The switcharms 525, 526, 527, 528, 528', 515, 516, 518 take a step forward the moment the relay 501 is reenergized, this taking place immediately by the action of the calling subscriber's impulse transmitter. When the switcharms of the side switch have reached their second position, the turning magnet 503 of the final selector is connected to the impulse contact 99 of relay 500 through the switcharm 526. The calling subscriber now sends in the rotary impulses which cause the brushes 504, 505 and 506 to be turned, and to be moved on to the contacts of the desired line, which we have assumed to be idle. The moment the changeover impulse is sent after the brushes have been moved on to the contacts of the wanted line, the armatures of relay 501 retract, and the circuit is closed from the negative pole of the battery through contact 106, test relay 520, contact arm 527 of side switch, to wire 107 and test brush 506. As the desired line is idle, the test brush 506 will not be connected to earth through the test contact leading to the desired line, and therefore the test relay 520 will not be energized. Therefore contact 108 will not be closed, and the impulse that is sent from the negative pole of the battery through 96, 97, 98, 519, 507 to earth will not be maintained at 108, but will stop flowing the moment the relay 501 reattracts its armatures so that the side switch magnet 519 will allow the contact arms of the side switch to pass into their third position, and thus close the ringing circuit, which may be traced from the negative pole of the battery through contact 99, contact arm 526, interrupter 545, ringing relay 524, to the positive pole of the battery. The interrupter 545 now causes the relay 524 to connect the line leading to the wanted subscriber to a source of ringing current 548 at regular intervals. When the wanted party responds, his switchhook momentarily establishes a connection between either of the limbs of his line and ground, and this causes the differential relay 522 to momentarily attract its armature and close a contact 118, which causes an impulse to flow from the negative pole of the battery through 118, 119, 98, side switch magnet 519, contact 507 to earth. The contact arms of the said switch are then caused to move into their fourth position, and the arm 526 in moving out of the third position opens the ringing circuit. Conversation may now take place. When the wanted subscriber responds, a current also flows through a relay 523, which is energized and opens a contact 122. The current which traverses the winding of relay 610 is insufficient to cause its energization as this relay will only operate when the line wires at the subscriber's station are short circuited, that is, when the subscriber at the station equipped as shown in Fig. 6, re-

sponds. This will be more fully explained hereinafter. If the called subscriber is the first to replace his receiver at the end of the conversation, a release circuit is closed at the contact 122, which may be traced from the negative pole of the battery through interrupter 521, wires 111, 121, contact 122, wire 123, switcharm 515, switcharm 514, which is now in position II, driving magnet 509, contact 508 to the positive pole of the battery. It must be mentioned that the driving magnet 509 received one impulse at the moment when the switcharms of the selector were moved out of their normal position by the first rotary impulse which caused the closure of the rotary off-normal switch 511, and resulted in an impulse flowing from the negative pole of the battery through the interrupter 512, contact 511, switcharm 514 in its position I, driving magnet 509, vertical off-normal contact 508 to the positive pole of the battery. This impulse caused the driving magnet 509 to send the switcharms and synchronous circuit changer from their positions I to II. We will now return to the restoring operation that was initiated by the wanted subscriber replacing his receiver on the switchhook and causing the relay 523 to be deenergized. It was seen that impulses then commenced flowing through the interrupter 521 and contact 122 to the driving magnet 509. These impulses also commenced flowing back to the group selector and the distributing switch through wire 304 and caused the synchronous circuit changers at the selectors to move synchronously with the circuit changer at the final selector. The release magnets at the final selector and at the distributing switch are energized at the moment in which the synchronous circuit changers pass from their positions III to IV and the release magnet 233 at the group selector is energized when the switcharms of the synchronous circuit changer pass from position V to VI. It will be remembered that the release magnets at the various selectors were connected to the wire 304 at the moment when the switcharm 513 passes from position III to IV, so that all the said magnets received an impulse through the arm 513 from the negative pole of the battery and caused the restoration of all the switches to their normal positions.

While the switcharms of the synchronous circuit changers were executing their synchronous movements in order to effect the restoration of the switches they also caused the metering circuit to be closed. This took place at the moment when the synchronous circuit changer at the final selector passed from position II to III. At this moment the switcharm of the synchronous circuit changer at the distributing switch also passed from position II to III and the switcharms of the synchronous circuit

changer at the group selector passed from position IV to V. Thus a current flowed from the negative pole of the battery through switcharm 513, contact 125, 114, 516, 304, 303, 302, 232, 230, 570, 78, 58, 70, 257, 252, 57, 56, 59, 61, 126, 210 and through the particular meter 206, 207, 208, 209 that is connected to the meter circuit 210. Conversation is thus charged to the party that initiated the call. It will be observed that if the contact arms of the side switch at the final selector had not gone into the talking position, no connection would have been established between the contact 125 and the wire 304 through the contact arm 516 of the side switch, and then no conversation is charged.

It will now be assumed that the desired station is a station that is connected to the calling line,—that is, that the calling subscriber is making a revertive call. The moment the rotary movement of the brushes 504, 505 and 506 commences, a rotary off-normal switch 511 is closed, which connects an interrupter 512 to the driving magnet 509 of a synchronous circuit changer allotted to the final selector. This circuit changer has two switcharms 513 and 514. It will be noted that when the rotary off-normal switch 511 is closed, the interrupter 512, in addition to being connected to the driving magnet 509 is also connected to the test wire 304, which extends back to the group selector and to the distributing switch. Thus the moment the switch 511 is closed an impulse will flow through the driving magnets 509, 227 and 62 of the synchronous circuit changers at the final selector, group selector and distributing switch. This results in the synchronous movements of the three circuit changers, and while the synchronous circuit changer of the final selector executes the second half of its travel from the contact I to II, its switcharm 513 momentarily connects the negative pole of the battery to the test wire 304. While the synchronous circuit changer at the final selector travels from position I to II, the circuit changer at the group selector travels from position III to IV, and the circuit changer at the distributing switch travels from its position I to II. Thus the switcharms 513, 78 and 61 will simultaneously brush past contacts 530, 529 and 100 respectively. The momentary connections at the three points just mentioned results in an impulse flowing from the negative pole of the battery through 513 and 530, 304, 303, 302, 232, 529, 78, 58, 252, 57, 56, 59, 60, 61, 100, 101, relay 221, resistance 531, contact 52, to earth. The relay 221 is energized, and closes a locking circuit for itself through its armature contact 102. By opening its contact 103, the relay 221 removes the busy condition of the calling line by disconnect-

ing the earth from the test wire 256, but the relay 221 also closes a contact 104, and thus connects a relay 222 through 104 and 53 to the wire 202 of the calling line. The 5 relay 222 is immediately energized, and by closing its contact 105 immediately reconnects the earth to the test wire 256, and thus replaces the busy potential, which has been removed by the opening of the contact 103. 10 The relay 222 is the revertive connecting relay, its function being to momentarily remove the busy condition of the calling line in the case of a reverted call, so as to enable revertive connections to be established. Its 15 operation will be more fully described presently.

It will be noted that the revertive connecting relay 222 is connected to the one limb of the calling line the moment the rotary impulses for stepping the final selector on to the wanted line, which in this case is also the calling line, commence coming in. After all the rotary impulses have been sent in, the changeover impulse will ensue, this ordinarily resulting in the wanted line being tested as to its idle or busy condition. The 20 test circuit at the final selector is established by the changeover impulse causing the relay 501 to be deenergized, and may be traced from the negative pole of the battery through the armature contact 106, test relay 520, side switchcharm 527, wire 107, brush 506, test wire 256, which is connected in multiple to the contacts in the contact banks of 25 all the other final selectors in the same group. In the case of a revertive call, however, the calling line momentarily removes the busy condition from its test wire by means of the revertive connecting relay 222 30 by opening its contact 105. From the moment in which the rotary impulses commence turning the brushes of the final selector to the contacts of the wanted line—that is, from the moment the driving magnet 509 of 35 the synchronous circuit changer at the final selector receives an impulse from the interrupter 512, due to the closure of the rotary off-normal switch 511, which causes the switchcharms 514 and 513 of the synchronous 40 circuit changer to travel from their position I to II—relay 222 at the distributing switch is energized. The excitation of the relay 222 is caused in the manner described above by the switchcharm 513 sending an impulse through contact 530 of the final selector to the distributing switch. After the 45 revertive connection relay 222 had been connected to the one limb of the calling line, further rotary impulses would generally 50 flow through the relay 500. During the flowing of these impulses, the limb 202 of the calling line will be kept earthed, so that the relay 222 is kept constantly energized. After the rotary impulses have all been sent in 55 and the switchcharms 504, 505, 506 have

reached the contacts of the wanted line, which in this case is also the calling line, a changeover impulse will ensue, this being caused by earthing the wire 201, and at the same time opening the limb 202. This causes 70 the simultaneous deenergization of the relay 501 and the revertive connecting relay 222. The revertive connecting relay opens its contact 105 and momentarily removes the busy test, so that no current will flow through the 75 busy test circuit which, as will be remembered, is to be traced from the negative pole of the battery through 106, 520, 527, 107, 506, 256, 105, 52, to earth. As the side switch magnet 519 is not kept energized by 80 the contact 108 of the test relay at the final selector, the switchcharms 525, 526, etc. of the side switch move into their third position. In this position of the switchcharms, the ringing relay 524 at the final selector is intermittently energized by a current flowing from the negative pole of the battery through 99, 526, 545, 524 to the positive pole. A ringing current will now be sent through 85 contacts 546, 547, to the wanted station. It 90 will be preferable to use selective ringing currents that cause only the bell of the wanted station to ring. Any known method of applying the proper selective ringing current may be used, and as the devices used 95 for this purpose form no part of the present invention, they will not be described. In the drawings a single ringing current source is shown at 548. From this point on the operation is the same as that described in connection with an ordinary call. 100

At the moment when the brushes 504, 505 and 506 of the final selector reach the contacts of the wanted line, a relay 523 will be energized if the call is a revertive one. If 105 the call is not revertive, the relay 523 is only energized when the wanted station responds. In any case the relay 523 is energized before the side switchcharms 515 and 516 move into their fourth position. By opening the contact 122 and thus opening the circuit from the interrupter 521 through 111, 121 to 123 before the called party answers, current impulses are prevented from flowing from the interrupter 521 through the driving magnet 110 509 and through the driving magnets of the other synchronous circuit changers, and thus causing prematurely the release which should take place later when the called subscriber replaces his receiver after having 115 responded to the call. The restoration of the apparatus takes place in precisely the same manner as in the case of an ordinary call, and will not therefore be described. 120

As previously indicated, relay 610 will 125 operate only when the line loop is short circuited at the subscriber's station. Thus when the called line is the station shown in Fig. 6 and this subscriber answers by removing his receiver, the resulting upward move- 130

ment of the switch hook momentarily short circuits the line loop as indicated in Fig. 6. This short circuiting of the line does not affect the differentially wound relay 522, but operates relay 610 and 523. The operation of relay 610 closes a circuit from battery through 611, 119, 98 and 519 to ground. This moves the side switch arms from the ringing to the talking position in a manner identical to that described in connection with the operation of the differential relay 522, which operates whenever any one of the other three subscribers on the line responds. Relay 610 is so designed that it can be adjusted not to operate when the one line lead 201 of Figs. 4 and 7 is connected to earth through the resistances 605 and 606 respectively, or when the line loop is closed through the transmitter and winding 609 of the induction coil. If an ordinary relay were used to perform the function required of relay 610, Fig. 3, considerable difficulty would be experienced in adjusting the relay so that it would release its armature after the same had been pulled up because this relay is not completely deenergized after the line loop has been short circuited by the springs 600" and 601", but is kept energized by a relatively weak current which subsequently flows through contact 607, transmitter 608 and the induction coil 609. To insure a proper release of the armature of relay 610, this relay may be specially constructed as shown in Fig. 10. As illustrated, the relay has in addition to the contact 611, which is used to close the circuit of relay 519, Fig. 3, another contact 612 and a link 613 which turns on a pivot 614 and is hinged at 615. When the relay is energized, the armature 612 sweeps against the lower end of the oblique surface 616 and pushes the link 613 aside. As soon as the armatures 611 and 612 are fully attracted, 612 makes contact with 618 and thereby short circuits the winding of relay 610 through a connection 619. The armature of the relay, therefore, is pulled back by the spring 620 but the short circuit through the contact 612 and lead 619 is not removed until the link 613 has been raised a considerable distance by the armature 612. As soon as the armatures have returned to practically normal position, the upper end of the oblique surface 616 engages with a pin 621 and the link 613 is then pushed aside sufficiently to liberate the armature 612 from the catch 622. As the armatures have now retracted a considerable distance from the magnetic pole of the relay, there is no danger of the armatures being reattracted by the relatively weak current which now flows through the winding of the relay 610.

In the circuits described above, the revertive connecting relay 222 that removes the busy condition at the moment a revertive

connection is established remains connected to the one side of the line 202 during the conversation. In Fig. 1, however, circuits are indicated by which the relay 222 may be disconnected from the line as soon as it has accomplished its purpose. This can be done by providing an additional position on each of the synchronous circuit changers at the distributing switch group selectors and final selector. This additional position would be arranged between the positions I and III of each synchronous switch. The circuits at the final selector would then be so arranged that at the moment when the switcharms 525, 526, etc. of the side switch move from their second into their third position,—that is, into the ringing position—the driving magnet 509 of the synchronous circuit changer receives an impulse which causes the switcharms 514 and 513 to move from their position II to the additional position. This impulse would also cause the synchronous circuit changer at the group selector to move from its position IV to the additional position, and would result in moving the switcharm 61 at the distributing switch from position II to the additional position. In executing the second half of this additional step, the switcharm 513 at the final selector momentarily connects the negative pole of the battery to the wires 304, 232 and 58, and this connection to the negative pole of the battery would be extended over 57, 56, 59, 60, 61 to the wire 120, which is connected to a contact located at the additional position of the circuit changer at the distributing switch. This momentary connection of the wire 120 to the negative pole of the battery would cause the relay 221 to be shortcircuited so that it would open its armature contact 104, and thus would disconnect relay 222 from the line limb 202.

What I claim is:—

1. In a telephone exchange system, the combination with a plurality of lines, automatic selector switches adapted to interconnect the same, meters for said lines, electromagnetic means associated with each of said switches adapted to release the same, a circuit adapted to actuate the meter of the calling line, a circuit adapted to actuate said electromagnetic release means, said circuits being closed over the same conductor which is associated with said meter and said electromagnetic release means at different times to actuate the same, and synchronous switches adapted to associate the same therewith at the proper times.

2. In a telephone exchange system, the combination with a plurality of party lines, automatic selector switches adapted to interconnect the same including group and final selector switches, meters for said lines, electromagnetic means associated with each selector adapted to release the same, electro-

magnetic means for establishing a busy condition on the multiple terminals of the calling line in said final selector switches upon the initiation of a call, electromagnetic means for removing said busy condition, a circuit adapted to actuate the meter of the calling line, a circuit adapted to actuate said electromagnetic release means, a circuit adapted to actuate said electromagnetic busy-condition removing means at the moment of test by said final selector, said circuits comprising the same conductor associated with said different electromagnetic means at different times to actuate the same, and means for so associating the same therewith at the proper times.

3. In a telephone exchange system, the combination with a plurality of party lines, automatic selector switches adapted to interconnect the same including group and final selector switches, meters for said lines, electromagnetic means associated with each selector adapted to release the same, electromagnetic means for establishing a busy condition on the multiple terminals of the calling line in said final selector switches upon the initiation of a call, electromagnetic means for removing said busy condition, a circuit adapted to actuate the meter of the calling line, a circuit adapted to actuate said electromagnetic release means, a circuit adapted to actuate said electromagnetic busy-condition removing means at the moment of test by said final selector, said circuits comprising the same conductor which is associated with said different electromagnetic means at different times to actuate the same, and synchronous switches adapted to associate the same therewith at the proper times.

4. In a telephone exchange system, the combination with a plurality of party lines, a meter for each party of a line, a circuit for operating the meters, electromagnetic means actuated upon the initiation of a call by one of the parties of a party line for preparing the corresponding meter for operation, and means for thereafter closing said meter circuit to actuate the selected meter.

5. In a telephone exchange system, the

combination with a plurality of lines, automatic selector and distributing switches adapted to interconnect the same, a meter for each party on a line, a circuit for operating said meters, electromagnetic means actuated upon the initiation of a call by one of the parties of a party line for preparing the corresponding meter for operation and for causing the operation of one of said distributing switches to seek a first selector and means for thereafter closing said meter circuit to actuate the selected meter.

6. In a telephone exchange system, the combination with a plurality of party lines, a meter for each party of a line, a circuit for operating the meters, electromagnetic means actuated upon the initiation of a call by any of the parties on a line for preparing the corresponding meter for operation, one of said parties causing the corresponding meter to be prepared by the simple closure of the line loop, and electromagnetic means actuated by any of the other parties in initiating a call and before the closure of the line loop to prevent the meter of the party prepared by the closure of the line loop from being so prepared.

7. In a telephone exchange system, the combination with a plurality of four-party metallic telephone lines, a meter for each party of a line, a circuit for operating the meters, electromagnetic means adapted to be actuated in four different ways by four different electrical conditions caused by the initiation of calls by said parties for preparing the corresponding meter for operation, one of these being the simple closure of the line loop, and electromagnetic means actuated by the creation of each of the other three conditions to prevent the preparing of the meter circuit of the line whose meter circuit is closed by the closure of the line loop upon the subsequent closure of such loop by any of the other parties.

In witness whereof, I hereunto subscribe my name this 30th day of April A. D., 1913.

FRITZ ALDENDORFF.
